UNITED STATES PATENT OFFICE.

HARRY C. KINSEL, OF ALTOONA, PENNSYLVANIA.

SWITCH-OPERATING MECHANISM.

No. 920,964.

Specification of Letters Patent.

Patented May 11, 1909.

Application filed October 31, 1908. Serial No. 460,408.

To all whom it may concern:

Be it known that I, HARRY C. KINSEL, a citizen of the United States, residing at Altoona, in the county of Blair and State 5 of Pennsylvania, have invented certain new and useful Improvements in Switch-Operating Mechanism, of which the following is a specification.

This invention relates to switch operating devices of the type in which the switch point is "thrown" by means of a foot-operated lever carried by the platform of a car, and one of the principal objects of the invention is to provide a switch point 10 thrower that will be automatically raised to an inoperative position after the switch has been thrown, thereby raising the same 15 out of the path of any obstruction that may be on the track bed.

In carrying out the above and other objects of the invention, it will of course be understood that the essential features of the same are susceptible of structural changes and arrangements of parts, a preferred and practical embodiment of which 20 is shown in the accompanying drawings, wherein—

Figure 1 is a top plan view of a portion of a car showing the platform of the same 25 equipped with the improved point thrower, and also showing a switch and its operating rod. Fig. 2 is a longitudinal sectional view taken on the line 2—2, Fig. 1. Fig. 3 is a front elevation of the mechanism shown 30 in Fig. 2.

Like characters of reference designate 35 corresponding parts.

In the embodiment of the invention shown in the accompanying drawings, 10 designates the roadbed, 11 the tracks thereon, and 12 the switch point. The switch point 12 is provided with an operating rod 13 that extends horizontally across the roadbed 10, and at the central portion of the 40 latter, the said operating rod is provided with an upstanding pin 14 which extends into a central, elongated, slot 15 formed in a plate 16 on said roadbed. The said slot 15 is considerably wider than the diameter 45 of said pin, to permit of a pin-shield or button 17 being placed over said pin and which has its head projecting through and above said plate. The lower portion of said shield 50 is provided with an outstanding flange 18 which engages with the underside of said plate to prevent said shield being with-

drawn upwardly through the slot. A coiled spring 20 is carried by the pin 14, the said spring exerting a pressure on said shield 17 which retains the same in a position with 55 its head projecting above the plane of the said plate.

The mechanism for "throwing" the switch has been shown as carried by a platform 21 of a car, said platform being provided at its underside with a plate 22 from which bolts 23 depend and form supports for a guide bracket 24, the top plate 25 of which is engaged by said supporting bolts and which form seats for cushioning springs 26 coiled on said bolts and whose upper ends bear on the platform plate 22. Said guide bracket 24 is in the form of a tube and is provided at its intermediate portion with vertical slots 27 and at its lower end with 60 an externally tapering annular toothed surface 28. A rod 29 extends through said guide bracket 24 and also through the platform, and is provided with a foot lever 30 through the medium of which said rod may 65 be turned, as will be presently explained. The lower portion of said rod 29 projects beyond the bottom of the guide bracket 24 and has its end projected forwardly in a horizontal plane to form a toe 31, the rear 70 end of which is notched or cut-away, as indicated at 32.

A collar 33 is adjustably mounted on the portion of said rod 29 within the upper 75 part of the guide bracket 24, said collar being provided with an outstanding ear 34 which projects through one of the slots formed in said bracket, and has pivoted thereto a pendent lock lever 35 provided with a toothed surface 36 at an intermediate 80 point of its length and at its end with a horizontally arranged shoe 37 which is of a substantial V-shape to provide outwardly flaring side wings 38. A lifting spring 40 is coiled on said rod 29 within the guide 85 bracket, the lower end of the said spring resting in a seat 41 formed in the tapering toothed portion of the bracket, and the upper end bearing on the collar 33.

Normally the parts of the switch throwing mechanism are in the positions shown in Fig. 2 of the accompanying drawings, the pendent lever 35 having its toothed portion in engagement with the teeth formed on the tapering end of the guide bracket 24, 90 and its shoe 37 just behind and in substantially the same horizontal plane as the toe 95

31 of the rod 29. When it is desired to throw the switch point 12, the operator turns the foot lever 30 carrying with it the rod 39 and its toe 31 to throw the pin shield 5 17 in the required direction. The contact of the said shoe with said pin shield is a sliding one which continues until the notched portion 32 is reached, whereupon the said shoe will clear said pin shield, and 10 immediately thereafter one of the flaring wings 38 of the shoe 37 will have a sliding contact with the pin shield which causes the pendent lever to swing backward and disengage its teeth 36 from the toothed portion 15 of the guide bracket 24. As soon as this disengagement occurs, the pressure of the spring 40 will cause the rod 29 to move upwardly through said guide bracket so as to clear its shoe from any obstruction that may 20 be on the roadbed. To re-set the mechanism, a downward pressure on the end of the rod 29 which projects through the platform 21 will force said rod to a position where its shoe will again be brought into engagement 25 with the pin shield, and the pivoted pendent lever 35 will swing automatically to a position to cause its teeth to engage with the toothed portion of the guide bracket and thereby hold the entire mechanism in a "set" position.

Claims:—

1. In a switch operating mechanism, the combination with the switch-point operating rod carrying a projecting element, of a thrower device consisting of a rotatable spring-lifted rod having a toe for engagement with said projecting element, and an automatically released lock for holding said rod depressed against the tension of its lifting spring.
2. In a switch operating mechanism, the combination with the switch-point operating rod carrying a projecting element, of a thrower device consisting of a rotatable 45 spring-lifted rod having a toe for engagement with said projecting element, and an automatically released lock comprising a relatively fixed toothed surface and a lock lever carried with said rod and having an interlocking engagement with said toothed surface.
3. In a switch operating mechanism, the combination with the switch-point operating rod carrying a projecting element, of a thrower device consisting of a rotatable 50 spring-lifted rod having a toe for engagement with said projecting element, and an automatically released lock comprising a rel-

atively fixed toothed surface and a lock lever carried with said rod and having an interlocking engagement with said toothed surface and being also provided with a member for engagement with said projecting element.

4. In a switch operating mechanism, the combination with the switch-point operating rod carrying a projecting element, of a thrower device consisting of a rotatable spring-lifted rod having a toe for engagement with said projecting element, and an automatically released lock comprising a relatively fixed toothed surface and a lock lever carried by and depending behind said rotatable rod and having an interlocking engagement with said toothed surface and being also provided with a member for engagement with said projecting element.

5. In a switch operating mechanism, the combination with the switch-point operating rod carrying a projecting element, of a thrower device consisting of a rotatable spring-lifted rod having a toe for engagement with said projecting element, and an automatically released lock comprising a relatively fixed toothed surface and a lock lever pivoted to said rotatable rod and having an interlocking engagement with said toothed surface, said lock lever being also provided with a shoe for engagement with said projecting element.

6. In a switch operating mechanism, the combination with the switch-point operating rod carrying a projecting element, of a thrower device consisting of a guide bracket having a spring-lifted rod slidably and rotatably mounted therein, and an automatically released lock comprising a toothed surface formed on said guide bracket and a lock lever pivoted to and depending behind said spring-lifted rod and provided with a toothed portion adapted to interlock with the toothed surface of said bracket, and a shoe carried by said lock lever and adapted to contact with said projecting element to release said lever from engagement with said bracket.

7. In a switch operating mechanism, the combination of the switch-point operating rod carrying an upstanding pin, a spring supported shield loosely fitting over said pin, and a thrower device.

In testimony whereof I hereunto affix my signature in the presence of two witnesses.

HARRY C. KINSEL.
